ELECTROLYTIC CONDENSER VENT

William G. Pontis and Paul F. Kochly, Dayton,
Ohio, assignors to General Motors Corporation,
Detroit, Mich., a corporation of Delaware

Application May 28, 1937, Serial No. 145,270

3 Claims. (CL 228—44)

This invention relates to electrolytic condensers and more particularly to means for venting the interior of the condenser upon an increase of internal pressure approaching the exploding point. It is an object of the present invention to provide a blow-out plug as a venting means for excessive pressure within an electrolytic condenser. Another object of this invention is to provide a method of seating a vent plug for electrolytic condensers. Another object is to provide a releasable vent plug for an electrolytic condenser, by fitting a plug within an aperture so as to engage the walls of the aperture with sufficient firmness to remain in position for all normal pressures, but which plug is adapted to be unseated upon development of excessive pressure. A further object is to provide a plug for closely fitting an aperture in a lid member for an electrolytic condenser, which plug will be self securing due to the cooperative properties of lid material and plug, pressing the plug in place for all normal pressures, but which plug is adapted to be unseated upon development of excessive pressures. A further object is to provide a closure member for vent hole in electrolytic condensers, that, when pressed into place, will be self seating to withstand normal pressures developed within the container, but that will unseat under excessive pressure conditions. Further objects and advantages of the present invention will be apparent from the following description, reference being had to the accompanying drawing wherein a preferred embodiment of the present invention is clearly shown.

In the drawing:

Fig. 1 is a side view of an electrolytic condenser embodying the instant invention, partly in elevation and partly in section, with parts removed for clearness. The view is indicated by the line and arrows 1—1 of Fig. 2.

Fig. 2 is a top plan view of the condenser.

Fig. 3 is a vertical sectional view on a larger scale of a fragment of the condenser lid, showing the vent plug being unseated.

Fig. 4 is a similar view but showing the plug as being completely unseated.

Fig. 5 is an enlarged detail view of the sealing plug in section, before pressing into place.

Fig. 6 is a bottom plan view of the venting plug means.

Electrolytic condensers in service, when subjected to high voltage currents, undergo considerable temperature changes which result in expansion and contraction of the electrolyte. In some instances, due to various causes, pressures within the electrolytic condenser develop to the point at which the unit may blow up, or explode. As a matter of safety, it has long been the practice to provide the sealed containers with venting means, which practice has customarily made use of a punctured membrane disposed over a passage-way, that is normally closed, but which opens up under extreme pressure conditions within the condenser, and thereby relieves the pressure within. That form of vent is unsatisfactory, inasmuch as it makes possible for leaks of the electrolyte, that results in an early failure of the cell, in that its capacity changes, or in that it becomes wholly useless. Following that leakage, or escape of electrolyte, corrosion of metallic parts and short circuit of the elements are sure to occur.

The herein described venting means constitutes an improvement over any known venting means, in that it operates to maintain the cell completely sealed for all conditions of the condenser use below the danger point, but upon the development of excessive pressure unseals the container, so as to prevent blow-up or exploding.

With particular reference to the drawing 18 indicates a can or container within which a condenser unit is enclosed, and which can is provided with a flange 12 at its open end, telescopically received by a ring member 14, having an inwardly directed flange 16 secured within the body 30 of a lid member 18 by molding the lid of moldable composition so as to partly embed the flange 16 of the ring substantially as shown in Fig. 1. At the time of forming the lid 18, it is also cast about anchorage portions 28 provided by a number of 35 terminal posts 22. The number and arrangement of the terminal posts 22, varies as the conditions warrant for adaptation in the electrolytic condenser unit. A sufficient number of the binding posts 22 protrude through the body of the lid 18, 40 somewhat as indicated at 24, and make provisions for connection with a conductor tab 26, leading to the electrodes of the electrolytic condenser. This is all illustrated in Fig. 1 of the drawing, except that the electrodes of the condenser, have 45 been omitted for clearness of illustration. The condenser can or container 18, with a lid so constructed, is assembled and maintained in sealed or air tight relation, by means of solder applied at the juncture 28 of the ring 14 and a peripheral 50 rib 38, formed near the open end of the container.

The venting means comprises an aperture through the lid of the container, and in the present instance is exemplified by a counterbore, the smaller diameter 48 of which opens on the interior 55

side of the lid, and is axially joined with a larger bored portion 42 opening on the exterior side of the lid, thus forming a plane like shoulder 44 at the juncture of the small and large bore portions.

5 In the form of invention illustrated, a sealing member is provided that constitutes a cup 58, substantially as illustrated in enlarged detail in Figs. 5 and 6. The cup-like member 58 is provided with a flat bottom 52, and very slightly 10 tapered flanged side walls 54. This cup-like plug is so fashioned that the peripheral edge 56 is slightly larger in over-all dimension than the portion of the flange joining the flat portion 52. In other words the side walls 54 flare outwardly very 15 slightly as they progress from the flat wall 52. That is illustrated in an exaggerated fashion by the dot-and-dash lines in Fig. 5. The plug 58 is so fashioned as respects the portion 42 of the counterbore, that the peripheral edge 56 is very 20 slightly oversized, thus necessitating that the plug 58 be press fitted within the aperture 42. As respects the plug, it is fabricated from material soft as compared with the material of the lid 18, so as to have sufficient yielding properties to follow any 25 generally irregular portions in the side walls of the counterbore, or so as to compensate for variation in the counterbore, under which circumstances the plug will then perfect the desired seal when pressed into place.

30 By "soft" as stated above, that quality of relative hardness is meant that it is slightly less than the surface or spin hardness of the composition forming the head. Under such conditions and properties, the plug, when pressed into place takes 35 a dead set, by reason of the further drawing operation perfected by the sidewalls of the counterbore, as the plug is pressed into place. Suitable material for a plug of that character may be a zinc alloy, sheet lead, brass or aluminum, de- 40 pending on the nature of the electrolyte to be used. The material used for the plug should be one not subject to contamination or corrosion by the electrolyte.

When an electrolytic condenser fitted with one 45 of these improved venting means is placed in service, the seating means will remain in position for all normal working conditions, but upon the development of excessive pressures within the container, then the increased pressure operating through the aperture 48 will unseat the plug in the manner suggested by Figs. 3 and 4, that results in relieving the excessive pressure developed within the container.

The vent plug herein described is made of a 50 material and of a shape that compensates for normal variations in hole and plug sizes and at

the same time maintains within definite limits the required tightness to fit. That is for the purpose of controlling the venting of pressure within specified limits, thus precluding the possibility of explosion.

5 The foregoing is accomplished in the following manner: The plug being of cup-shape with the press fit diameter located at the open end, away from the rigid bottom, together with the ductility of material lends itself readily to diameter variations in the hole into which it is pressed.

In this case where the plug is pressed into the lid of Bakelite or of other molded material, the hole size and shape is not substantially changed. 15 Where the diameter of the plug is to the large limit and the hole to the small limit, the action of pressing the plug into the hole is likened to that of a second drawing die operation, that reduces the plug diameter in relation to the hole. 20

The plug being soft, yields to diameter variations, taking a reduced diameter set. From here on the tightness of press fit is controlled by the thickness of material. To increase the tightness of fit, it is only necessary to increase the 25 thickness of material.

While the embodiment of the present invention as herein disclosed, constitutes a preferred form, it is to be understood that other forms might be adopted, all coming within the scope of the 30 claims which follow.

What is claimed is as follows:

1. In an electrolytic condenser, an electrolyte container having an end wall provided with an aperture therethrough adapted to serve as a vent, 35 and means frictionally secured within the aperture normally sealing the vent, and said means comprising a drawn metal cup whose flange diameter is greater than the diameter of the aperture, and tends to bite into the walls of the 40 aperture when subjected to unseating pressure from within.

2. The combination set forth in claim 1, in which the sealing means comprises a metal cup having an outwardly flaring rim that is press 45 fitted into the aperture of the end wall so that the rim edge engages the wall of the aperture.

3. The combination set forth in claim 1, in which the sealing means comprises a dished member inserted in the aperture of the end wall, which member has been further deformed so that its edges frictionally engage the walls of the aperture.
